SOUND RECORDING APPARATUS

Edward W. Kellogg, Moorestown, N. J., assignor
to Radio Corporation of America, a corporation
of Delaware

Application January 5, 1935, Serial No. 531

3 Claims. (Cl. 179—100.3)

This invention relates to improvements in sound recording apparatus, and more particularly in the variety thereof which is used in re-recording from an original sound record to a duplicate sound record adapted either for the production of prints or for direct sound reproduction.

One object of the invention is to provide a method and apparatus for producing what is known as an anti-ground-noise sound record from an ordinary sound record.

Another object of the invention is to provide a method and apparatus for producing such an anti-ground-noise record which is capable of direct sound reproduction.

Another object of the invention is to provide such a method and apparatus as will permit the use of a properly designed amplifier including appropriate time lag in the operation thereof to prevent oscillation or response to audio-frequency impulses in the operation of the anti-ground-noise shutter, in combination with a reproducing system for the operation thereof from an original sound record which will cause the shutter to be operated at the same time as the sound being recorded.

Another object of the invention is the provision of a new type of galvanometer which will simultaneously record sound waves and provide the blackened anti-ground-noise area on the sound track.

The invention is particularly adapted to use with sound records of the variable area type.

My invention involves an improvement upon the method and apparatus shown and described in Greentree Patent 1,971,181 and McDowell Patent 1,855,197, and provides for the re-recording of sound from a photographic record to another photographic record, thereby permitting such modification of the characteristics of the record as may be desirable in the electrical amplifying circuits used in the re-recording, and further involves the application of ground noise elimination to such re-recording apparatus and method.

In the preferred form of the invention, I provide a particularly novel and convenient re-recording galvanometer having two mirrors similarly cooperative with the optical system for simultaneously but independently recording the sound waves, and a record corresponding to the envelope of the sound waves for the purposes of eliminating ground noise.

In the drawing:

Fig. 1 shows diagrammatically a re-recording apparatus for producing a negative sound record

of the anti-ground noise type adapted for the production of positive prints.

Fig. 2 shows the double galvanometer for the production of a positive anti-ground noise sound record directly.

Referring first to the system shown in Fig. 1, 1 indicates a sound record which is preferably a positive sound record of the variable area type, and which is moved downwardly past the gate member 2 which may be a curved plate or rotating drum or any of the usual types of sound gates provided it is adapted to sound take-off at two points separated by a short distance measured in the direction of travel.

The sound reproducing optical system consists of the usual type of exciter lamp 3, the condenser lens 4, the slit 5 and the objective lens 6 forming an image 7 of the slit 5 upon the film.

From this image 7, the light diverges to the photocell 8.

The current passing through the photocell 8 is amplified by an audio frequency amplifier 9 of any customary or usual type, and is then passed to the galvanometer 10 which is likewise of any type adapted to such sound recording. This galvanometer 10 includes a movable mirror 11 upon which light is directed from the lamp 12 by the lens 13. Lens 14 causes an image of the aperture 15 to be formed in the plane of the slit 16. The position of this image is determined by the angle which the mirror 11 makes with the incident light. Therefore, rotational vibrations of the mirror cause movements of the image. Light enters the lens 18 from only that portion of the slit 16 which is illuminated, or covered by the image of the aperture 15. Thus the movements of the mirror result in varying fractions of the slit 16 being illuminated, and the length of the line of light imaged on the film also varies in response to movements of the mirror. The film 19 is a photographically sensitive film of any type appropriate for the production of a sound record.

Before any given point of the soundtrack of the film 1 reaches the point 7, it passes the point 7' separated a predetermined distance from the point 7, as will be more particularly described later, and at this point there is another photoelectric take-off consisting of exciter lamp 3', lens 4', slit 5', lens 6', and photocell 8', all of which operate in the same manner as the corresponding elements of the sound take-off first described.

From the photocell 8' current passes through the amplifier 20 and then through the rectifying

amplifier 21, these two elements being preferably constructed in the manner shown and described in the article by Barton Kreuzer in the "Journal of The Society of Motion Picture Engineers" for June, 1931, pages 671 to 683, this issue of the said journal being volume 16, No. 6.

The output from the amplifier 21 goes to the galvanometer 22 which carries a shutter 23 adapted to cover up a portion of the slit 5 corresponding to the unused portion of the sound track upon the film 1. When the modulation is very slight, the shutter will move closer to the center and prevent the transmission of light through the transparent portion of the sound track above the peaks of the images of the sound waves, while if the modulation is increased, the shutter will unmask a correspondingly larger portion of the slit 5 in order to permit light to pass through the entire images of the sound waves.

The output from the amplifier 21 also passes through a galvanometer 24 which is similar in construction and operation to the galvanometer 22 and serves to mask off a corresponding portion of the light passed to the sound record strip 19 so that the portion of the sound record impressed upon the member 19, which would otherwise be black but unmodulated, is rendered clear and therefore a print therefrom upon a positive film will have, in addition to the black print of the sound record, a blackened portion corresponding to the portion of the sound record 1 which has been masked by the member 23.

It will be apparent that the effect of the member 23 will be to prevent the reproduction of ground noise from the clear or unmodulated portion of the sound track on the film 1, thereby preventing the recording of such ground noise upon the film 19, and at the same time the operation of the mask 25, in providing a correspondingly clear portion upon the film 19, will correspondingly prevent any ground noise from the film itself in the reproduction of prints made from the film 19.

The amplifier and amplifying rectifiers 20 and 21, plus the necessity of overcoming the inertia of the masks 23, 25 and their supporting members, necessarily introduce a certain amount of time-lag between the photocell 8' and the movements of the galvanometers 22 and 24, and the optical system 3'-6' is accordingly spaced from the optical system 3-6 a distance such that the time of travel of the film from the point 1' to the point 7 corresponds to this time lag and, therefore, the position of the masks 23 and 25 will at all times correspond to the amplitude of the sound record being then reproduced through the photocell 8 and amplifier 9.

Referring now to the construction shown in Fig. 2: It is sometimes desirable to record directly or to produce by a re-recording process, as described above, a sound record adapted to direct reproduction without making prints therefrom, and the apparatus shown in this figure is intended for the production of such sound records with the portion of the sound track blackened to correspond to the clear portion provided on the sound track of the film 19. This apparatus includes an optical system similar to that shown in the recording apparatus of Fig. 1, and including the slit 16, the lens 17, and the lens 18 which serve to direct the light from the mirror 11' in the manner already described.

For the galvanometer 10 and mirror 11, there is substituted, however, a double galvanometer 75 consisting of a movable coil 10' and a mirror

11' for recording the sound in the same manner as the coil 10 and mirror 11. Co-axial with this mirror 11', or substantially so, is a mirror 27 which serves to direct light from the same source, upon the slit 16, the limits of the light beam being defined by the same mask 15. This mirror 27 is operated by the coil 28 which moves between the pole pieces 29 of a magnet, the coil 28 being fed with current from the amplifier 21 in the same manner as the coil 24 shown in Fig. 1. It will be apparent that movement of the mirror 27 instead of producing a clear portion on the sound record 26 will produce a blackened portion, and by properly adjusting the position of the mirror, this blackened portion can be made to correspond to the clear portion produced on the film 19 so that the sound record produced upon the photographically sensitive film 26 can, after development, etc. be played directly in an appropriate sound reproducer, and with a reduction of ground noise corresponding to the reduced width of clear film, exactly as was the case with a positive print from the film 19.

It will be apparent that the double galvanometer of Fig. 2 is not limited to use in a re-recording apparatus as shown in Fig. 1, but that it can also be used in making original sound records for direct reproduction. It is also obvious that other electro-mechanical devices than the moving coils 22, 24, 28, or the magnetic armature devices 10, 10', may be employed to actuate the vanes 23, 25, or the mirror 27, or the mirrors 11, 11'.

Having described my invention, I claim:

1. Sound re-recording apparatus for producing a film sound record without ground noise, from a variable area film sound record having a substantially constant average light transmission, comprising means for passing a beam of light through said sound record, photoelectric means for receiving said light after it is passed through said record, means connected to said photoelectric means for producing a current corresponding to the envelope of the sound waves, means for directing a second beam of light through said sound record, photoelectric means for reproducing sound from the light transmitted through the film from said second means, means for directing a third beam of light onto unexposed film, means connected to said sound reproducing means for modulating the said third beam of light in accordance with sound vibrations, means in the path of the second said beam of light actuated by the current corresponding to the said envelope of the sound waves for obscuring the clear portion of the said sound record in accordance with the envelope of the sound waves to be reproduced, and means in the said sound recording optical system connected to the said envelope current producing means, for shading the portion of the sound record which is being produced in accordance with the sound impulses.

2. Sound re-recording apparatus for producing a film sound record without ground noise, from a variable area film sound record having a substantially constant average light transmission, comprising means for passing a beam of light through said sound record, photoelectric means for receiving said light after it is passed through said record, means connected to said photoelectric means for producing a current corresponding to the envelope of the sound waves, means for directing a second beam of light through said sound record, photoelectric means for reproducing sound from the light transmitted

through the film from said second means, means for directing a third beam of light onto unexposed film, means connected to said sound reproducing means for modulating the said third beam of light in accordance with sound vibrations, means in the path of the second said beam of light actuated by the current corresponding to the said envelope of the sound waves for obscuring the clear portion of the said sound record in accordance with the envelope of the sound waves to be reproduced, and means in the said sound recording optical system connected to the said obscuring means and the said envelope current producing means, for shading the portion of the sound record which is being produced in accordance with the sound impulses.

3. Sound re-recording apparatus for producing a film sound record without ground noise, from a variable area film sound record having a substantially constant average light transmission, comprising means for passing a beam of light through said sound record, photoelectric means for receiving said light after it is passed through said record, means connected to said photoelectric means for producing a current correspond-

ing to the envelope of the sound waves, means for directing a second beam of light through said sound record, photoelectric means for reproducing sound from the light transmitted through the film from said second means, means for directing a third beam of light onto unexposed film, means connected to said sound reproducing means for modulating the said third beam of light in accordance with sound vibrations, means in the path of the second said beam of light actuated by the current corresponding to the said envelope of the sound waves for obscuring the clear portion of the said sound record in accordance with the envelope of the sound waves to be reproduced, and means in the said sound recording optical system connected to the said envelope current producing means, for shading the portion of the sound record which is being produced in accordance with the sound impulses, the said two means for passing beams of light through the sound record being spaced longitudinally of the record by a distance corresponding to the time of the delay in the said envelope current-producing means.
